United States Patent Office.

WILLIAM D. WILSON, OF WATERTOWN, NEW YORK.

Letters Patent No. 78,347, dated May 26, 1868.

IMPROVEMENT IN HORSE HAY-FORKS.

The Schedule referred to in these Letters Patent and making part of the same.

TO ALL WHOM IT MAY CONCERN:

Be it known that I, WILLIAM D. WILSON, of Watertown, in the State of New York, have invented a new and useful Improvement in Harpoon Hay-Forks; and I do hereby declare that the following is a full, clear, and exact description of the same, reference being had to the accompanying drawings, and letters of reference marked thereon, making a part of this specification, in which—

Figure 1 represents a longitudinal central section.

Figure 2 a horizontal section on the line z , fig. 1.

This invention belongs to that class of devices used for spearing hay or other like crop, which are provided with prongs arranged so as to remain within the body of the instrument until after it has been forced into the vegetable mass, and then to partially emerge and bury themselves in the said mass, so that a large quantity of the latter may be taken up by the fork on its withdrawal.

To enable those skilled in the art to make and use my invention, I will now proceed to describe its construction and operation.

Similar letters in the drawings refer to like parts.

A represents a metallic tube of suitable size, provided, at its lower end, with a casing, a , in which are two curved passages, a' a' , wherein the prongs b b move. The said casing has a bayonet-point with four concave sides, c c , &c., that the instrument may be forced into the vegetable matter with greater ease.

Friction-rollers, d d , may be so placed in the passages a' as to facilitate the movement of the prongs b .

The upper and inner ends of the said prongs are suitably connected with the lower extremity of a rod, d , within the tube A, the upper end of which rod is attached to a plug, e , which nearly fills said tube, and has a head, e' . A spiral spring, h , is coiled around the rod d , between the plug e and casing a , which spring tends to force the rod d and plug e toward the upper end of the tube, and consequently to draw the prongs b within the casing, the stops i i in the passage a' limiting the movement of these parts due to the pressure of the spring by catching the inner ends of the prongs.

In a recess in the plug e is pivoted a lever, k , with a rounded stop, k' . The lever k receives a constant pressure outward from a spring, k'' . A tripping-lever, l , also provided with a circular head, l' , is suitably attached to the outside of the tube A, in which there is a slot for the lever k to project through. The casing a having been inserted in a mass of hay, the plug e is forced down by hand, causing the prongs b to emerge and enter the vegetable matter, said downward movement being continued until the head of the lever k passes below the head of the lever l , when the stop k' is immediately forced through the slot in the tube by the pressure of the spring k'' , and, passing under the head l' , is caught and held there. The instrument is then withdrawn with the hay taken up by the prongs b .

To drop the load, a cord, m , attached to the upper part of the tripping-lever l , is pulled downward, causing the circular head l' to rotate on the rounded stop k' , and forcing the latter in with the least possible friction. An arm, l'' , projects downward beyond the circular head l' , said arm being furnished with a screw, l''' , which may be set so as to come in contact with the stop k' at any desired moment during the rotation of the head l' , and carry said stop out of contact with the head l' , so as to release the spiral spring h and withdraw the prongs b from their load.

Having thus fully described my invention, what I claim as new, and desire to secure by Letters Patent, is—

1. The levers k l , in combination with the plug e , as and for the purpose set forth.
2. The levers k l , in combination with the arm l'' and screw l''' , in manner described.
